INVENTOR:

Henry Clay,
BY *John Diederich*,
ATTORNEY.

UNITED STATES PATENT OFFICE.

HENRY CLAY, OF PHILADELPHIA, PENNSYLVANIA.

TELEPHONE CALL-BELL.

SPECIFICATION forming part of Letters Patent No. 280,451, dated July 3, 1883.

Application filed September 21, 1882. (No model.)

To all whom it may concern:

Be it known that I, HENRY CLAY, a citizen of the United States, residing in the city and county of Philadelphia, State of Pennsylvania, 5 have invented a new and useful Improvement in Telephone Call-Bells, which improvement is fully set forth in the following specification and accompanying drawings, in which—

Figure 1 is a view of the interior of the box 10 containing the improvement in telephone call-bells embodying my invention. Fig. 2 is a vertical section thereof. Fig. 3 is a view of a detached portion. Fig. 4 is a detached view of the hook, &c., hereinafter described, and 15 proximate devices.

Similar letters of reference indicate corresponding parts in the several figures.

My invention consists of certain improvements in telephone call-bells, the construction, 20 operation, and advantages whereof will be hereinafter fully set forth.

Referring to the drawings, A represents the box of a telephone call-bell, in which is also contained the transmitter.

25 B represents the hook on which the telephonic ear-piece is hung, the same having an insulated axis, a, which is supported on the frame C within the box A. The end of the hook B within the box is formed with an inwardly-projecting nose, b, and an outwardly-projecting hook, c, with either of which is adapted to engage an insulated pin or stud, D, projecting laterally from a spur-wheel, E, which is mounted on a shaft, F, and meshes with a 30 wheel, G, the shaft H whereof carries a spur-wheel, J, which meshes with a pinion, K, whose shaft L has fixed to it the rotary armature M of the magnet N, the several shafts named being sustained on the frame C. The 35 shaft F also carries a ratchet-wheel, P, and a coiled spring, Q, both rigidly secured to said shaft, and engaging with said ratchet-wheel is a pawl, R, which is hung on the arm or lever of the bell-hammer to be hereinafter referred to.

40 Adjacent to the pawl R is pivoted an elbow-lever, S, the upper or outer limb of which projects under the pawl R, or is otherwise connected therewith.

To the wheel E, at a right angle to the axis 45 thereof, is pivoted a dog, T, one end of which is attached to the outer end of the coiled spring

Q, and the other end is adapted to engage with the lower or inner limb of the elbow-lever S.

V represents magnets between which vibrates the arm or lever W of the bell-hammer 55 X, the bell or bells Y being properly supported on the box A.

Z represents a spring for returning the hook B to its normal position, the same being properly secured to said hook and the frame C, and 60 Z' represents a pawl mounted on the frame C, and engaging with the ratchet-wheel P for preventing improper rotation thereof.

Suitable wires, d e, run from the armature M and magnet N, and wires f g run from the 65 hook B and magnets V to hooks A', which are secured to the rear of the box A.

A" represents the back board, which, attached to the wall or elsewhere, is adapted to sustain the box A and the parts thereof, said 70 board having plates A", with which the wires h, leading from the instrument to the place of service, are connected, said plates being so disposed that when the box is hung in position the hooks A' and the plates A" are in contact 75 and in electric connection.

The operation is as follows: As shown in the drawings, the ear-piece has been removed from the hook B, the spring Z having raised said hook, by which action the pin or stud D 80 is clear of the hook c and engaged by the nose b. The passage of the pin from said hook to the nose b sets the train of wheels in motion and rotates the armature M, the latter creating an electric current which rings the call-bell of the instrument desired for communication. After service the ear-piece is replaced on the hook B, and the weight of this piece draws the hook downward, and thus releases the pin or stud D from the nose b. Owing to 85 the spring Q, which has been properly adjusted previously, the wheel E now revolves until the pin or stud D is arrested by the hook c, the latter having been placed in the path of the pin or stud D by the downward motion of the 90 hook B. By the revolution of the wheel the train of wheel-work is put in motion, and the current generated passes through the magnets V, causing the armature W to vibrate and the bell-hammer X to strike the bells Y, and automatically disconnecting the wires at the central 95 office. This disconnection is effected by the 100

action of the electric current upon an automatic combination of devices described in my separate application for patent on a telephonic switch-board. The vibration of the armature 5 W operates the pawl R, which in turn winds the ratchet-wheel P, it being held or locked by the catch-pawl Z'. Since the ratchet-wheel P and spring Q are secured to the same shaft, it is evident that the spring Q will be wound 10 up. To prevent its being too tightly wound, I attach to the end of the spring opposite to that secured to the shaft F one end of the dog T, while the other end rests against the lower end of the elbow-lever S, as has been stated. 15 This end is so constructed as to encircle the shaft F, thus permitting the lower end of the dog T to be in constant contact with the elbow-lever S. The end of the elbow-lever S opposite to the end encircling the shaft F passes 20 under the pawl R. Should the spring Q now be wound too tightly, it will draw one end of the dog T toward the shaft F, thus forcing the elbow-lever S to raise the pawl R clear of the ratchet-wheel P, as may be distinctly seen in 25 Fig. 2. This having been done, it is evident that the bell may continue to be rung by the current without being retarded by the too close winding of the spring Q. The electric current enters the box through one of the 30 wires h and leaves it by the other. These wires are respectively attached to hooks A'—one on each side of the box. Wire g connects one of said hooks to magnet V, and a wire, d, connects said magnet to the revolving armature M of the generator. The electrical current, following the line of conductors thus far described, passes to and through permanent 35 magnet N, and thence through wire e to a contact-point or electrode, e'. When the telephone is hung on the hook, this electrode is in 40 contact with hook B, which is connected electrically with the other hook, A', thus completing the circuit, excepting the necessary external connections between the two wires h, h, 45 which need not be here described. The circuit in practice will sometimes be reversed, as it is equally operative, whichever may be the direction of the current. When the telephone is not on the hook B, the latter is drawn up 50 by spring Z, as shown, and the circuit is broken between it and electrode e'. The current cannot pass through the mechanism of the call-bell under such circumstances, but will pass down wire f to the said hook, and 55 thence directly away from said mechanism through electrical connections which need not here be described.

As described, that portion of the instru-

ment relating to the stud or pin D and nose and hook b c is for exchange-lines giving a 60 short alarm for "on" and long ring for "off." In using the instrument for private purposes, where the alarms are just the reverse, I place the extension of the hook B underneath the shaft F instead of overhanging the same, and 65 allow the stud or pin D to be at rest on the lower side. It is evident that thus I get the long ring upon removing the ear-piece and the short one upon replacing it. The current generated by the mechanism in one bell or 70 signaling-instrument is not sufficient to wind its motor. The spring Q is wound by the action of the armature-lever W and the intervening devices, said lever being caused to vibrate by the magnets V as their polarity is 75 changed by the current created by the generator of the central office or distant station. At the same time this current rings the bells Y by the strokes of hammer X, carried by said armature-lever. During this operation the 80 mechanism in case A is motionless, except said armature-lever, pawl R, carried thereby, wheel P, and arbor F, to which the inner end of the spring Q is attached. When the mechanism referred to within case A is in operation, it 85 partly winds its own spring Q, and also winds the corresponding spring of a distant instrument, as before stated, and of as many instruments as are in circuit. These devices are used in connection with a strong generator at 90 the central office, the main dependence being on the currents created thereby.

Having thus described my invention, what I claim as new, and desire to secure by Letters Patent, is—

95

1. In a telephonic call-bell, the hook B, formed with a nose, b, and hook c, in combination with the spur-wheel E, having a pin or stud, D, gearing G J K, the rotary armature M, and magnet N, substantially as and for the purpose set forth.
2. The hook B, in combination with the ratchet-wheel P, pawl R, arm or lever W of the bell-hammer, bell or bells Y, and magnets V, substantially as and for the purpose set forth.
3. The pawl R on the bell-hammer arm or lever, in combination with the elbow-lever S, dog T, coiled spring Q, the spur-wheel E, having a stud, D, and the shaft F, substantially as and for the purpose set forth.

HENRY CLAY.
